UNITED STATES PATENT OFFICE.

RENÉ H. GASPARD, OF CHICAGO, ILLINOIS.

VALVE ACTUATOR.

Application filed January 15, 1921. Serial No. 437,391.

To all whom it may concern:

Be it known that I, RENÉ H. GASPARD, a former citizen of France, who has forsaken his allegiance to France and declared his intention of becoming a citizen of the United States, and a resident of the city of Chicago, county of Cook, and State of Illinois, have invented certain new and useful Improvements in Valve Actuators, of which the following is a specification.

My invention relates to time-controlled valve mechanisms and it has for its principal object the provision of a form and arrangement of parts by which water may be admitted automatically at a given predetermined time to a bath-tub, means being provided for tempering the hot and cold water as it is admitted and for thereafter further tempering the water if it may be desired or

necessary.

Other objects will appear hereinafter.

The invention consists in the combinations and arrangements of parts herein-after described and claimed.

The invention will be best understood by reference to the accompanying drawings forming a part of this specification, and in which—

Fig. 1 is a front view of my improved mechanism, the front face of the cabinet within which the mechanism is placed being partly broken away for clearness of illustration, and a fragmentary portion of a tub being shown in position below the valve outlet,

Fig. 2 is a vertical section taken substantially on line 2—2 of Fig. 1,

Fig. 3 is an enlarged detail view being substantially a section taken on line 3—3 of

Fig. 2,

Fig. 4 is an enlarged detail view, being substantially a section taken on line 4—4 of Fig. 1, and

Fig. 5 is a fragmentary view of the valve operating means, substantially upon the line 5—5 of Fig. 2.

Referring to the drawings, 5 indicates a cabinet of any approved type enclosing a housing 6 to valve mechanism comprising a housing 6 to which hot and cold water are adapted to be fed by means of pipes 7 and 8 respectively, valves 9 preferably being transversely disposed and rotatably mounted in said pipes for controlling the flow of water through said pipes. As is shown in Fig. 3, the housing 6 is divided by a web 10 into two com-

partments, the upper one of which serves as a mixing chamber, being indicated by the numeral 11.

Means is provided for controlling the escape of water from the chamber 11 for admission to a bathtub 11' in suitable position below the housing 6, such means preferably comprising a clock 12 and operative connections between the clock and a suitable valve interposed in the partition 10 as hereinafter described by which the admission of water to the tub can be automatically effected at any time as may be determined in advance. For controlling the escape of water, I have provided a valve 13 comprising a valve stem 14 by an outward sliding movement of which the valve is opened for water to pass from the chamber 11. The valve stem 14 is pivotally connected at its outer end with one arm of a bell crank lever 15 which is pivotally mounted upon a horizontal bar 16 supported by the cabinet 5. The other arm of the bell crank lever 15 is pivotally connected to a vertical link 17, the upper end of which is pivotally connected to an arm 18 extending laterally from a sleeve 19 which is revolubly mounted upon a bar 20 extending forward from the rear face of the cabinet 5. An arm 21 rising from the sleeve 19 is pivotally connected to one end of a link 22, the opposite end of which is pivotally connected to the upper end of an arm 23 forming a part of the clock 12 and adapted to be operated thereby. The clock 12 is of any suitable construction and arrangement by which the arm 23 may be moved by the clock mechanism toward the right in Fig. 1 at a predetermined time as controlled by the position of the hand 24.

As will be readily understood, with the valves 9 opened so as to admit water to the chamber 11, and with the hand 24 set at the desired point, at the appropriate time the arm 23 will be given a movement toward the right in Fig. 1, serving to swing the arms 21 and 18 in clockwise direction in said figure for moving the link 17 downwardly, this movement serving to turn the bell crank lever 15 also in clockwise direction in said figure for drawing the valve stem 14 outwardly and permitting the water from the mixing chamber 11 to pass into the tub 11'.

Means is provided connecting the valves 9 so as to operate them in unison. This means comprises a horizontal bar 25 which is pivotally connected with the upper ends

of the arms 26 and 27 of the valves interposed in the pipes 7 and 8 respectively. As is shown in Fig. 2, the bar 25 is slidably mounted upon another bar 28 carried by the front face of the cabinet 5, the arrangement being such that by a sliding movement of the bar 25 the valves 9 are operated in unison. As is shown in Fig. 5, the arms 26 and 27 are provided with slots 26' 10 in their upper ends for their connection with the pins 27' on bar 25 whereby this operation is permitted. A handle 29 is provided rising from the bar 25 and extending through a horizontal slot 29' in the front 15 face of the cabinet 5 for effecting a sliding movement of said bar. The arrangement of the valves 9 is such that when the arm 26 or 27 of one of the valves is moved toward the other arm the valve is given a 20 closing movement, while a movement of such arm in the opposite direction serves to give the valve a movement to open it. With the arms in the position shown in Fig. 1, both of the valves 9 are in partially opened 25 condition so as to permit an equal flow of hot and cold water therethrough. When the bar 25 is moved toward the right in said figure, the cold water valve at the right is opened a trifle wider and the hot water valve 30 at the left is closed slightly. Upon the movement of the bar 25 toward the left, the flow of hot water is increased and the flow of cold water correspondingly decreased. By a movement of the bar 25 in either direction to the limit of its motion, the flow of 35 either the hot water or the cold water can be entirely shut off.

I have provided hand operated means for admitting water to the tub independently of 40 the clock-controlled means as above described. This manually controlled means comprises a valve 30 mounted upon a valve stem 31 which is adapted to be moved in the direction for opening the valve by means of 45 a hand wheel 32, the valve stem 31 having a screw threaded seat in the side of a housing 6 for effecting this result.

When it is desired that the tub 11' be 50 filled at a certain hour, the hand 24 is set accordingly, as is readily understood, and the bar 25 is at the same time set in position for causing the desired proportions of hot and cold water to be admitted to the chamber 11 through the valves 9. If it is found

that the water as admitted to the tub by the 55 clock-controlled valve mechanism is either too hot or too cold, the water can be further tempered as may be desired by the admission of the required amount of either cold or hot water, the handle 29 being given the requisite changed setting, and the additional water being admitted to the tub by the use of the manually controlled valve 30.

While I have illustrated and described the preferred form of construction for carrying 65 my invention into effect, this is capable of variation and modification without departing from the spirit of the invention. I, therefore, do not wish to be limited to the precise details of construction set forth, but 70 desire to avail myself of such variations and modifications as come within the scope of the appended claims.

Having described my invention, what I 75 claim as new and desire to secure by Letters Patent is:

1. In combination with a water mixing chamber; oppositely disposed pipes communicating with said chamber; spigots rotatably mounted in said pipes having apertures therein communicating with said pipes; extensions on said spigots; an operative connection having means slidably engaging said extensions; and means secured to said connection and arranged to move 80 rectilinearly, for indicating the relative positions of said apertures, substantially as described.

2. In combination with a water mixing chamber; a valve for closing said chamber; 90 oppositely disposed pipes communicating with said chamber; spigots transversely disposed and rotatably mounted in said pipes having apertures therein communicating with said pipes; angular extensions on said 95 spigots; an operative connection having means slidably engaging said extensions; and an indicator secured to said connection adapted to slide in a horizontal slot for indicating the relative position of said apertures. 100

In testimony whereof I have signed my name on this specification in the presence of two subscribing witnesses.

RENÉ H. GASPARD.
